DIVERGENT PLATE, LINK SUPPORTED, MOP
PRESSURE ACTUATED MOP WRINGER

David Jenkins, Seattle, Wash.

Application February 26, 1948, Serial No. 10,970

4 Claims. (Cl. 15—261)

1

This invention relates to a mop wringer for use in connection with a mop pail and an object of this invention is to provide an efficient device by which excess water can be quickly and easily pressed out of a mop with minimum effort on the part of a person using the mop and without requiring the user to put his hands in the water.

Another object is to provide a mop wringer comprising two divergent perforated plates hinged together to form a V-shaped or trough shaped receptacle and suspended in a mop pail by convergent links in a suitable position to receive a mop so that when a water saturated mop is placed between the two plates and a downward pressure exerted thereon the plates will be caused to exert an even pressure against the mop and squeeze any desired percentage of the water out of the same.

Other objects of the invention are to provide mop wringer means that is simple in construction, not expensive to manufacture easy to use and efficient in its operation of removing excess water from a wet mop.

Other objects of the invention will be apparent from the following description taken in connection with the accompanying drawings.

In the drawings

Figure 1 is a top plan view of a mop wringer constructed in accordance with this invention showing the same in a mop pail, a portion of the pail being broken away.

Fig. 2 is a view partly in section and partly in elevation looking in the direction of broken line 2—2 of Fig. 1.

Fig. 3 is a view similar to Fig. 2 showing this mop wringer as it may appear when a mop is applied thereto for wringing.

Fig. 4 is a fragmentary perspective view of one end portion of the mop wringer.

Like reference numerals designate like parts throughout the several views.

This mop wringer comprises two rectangular plates 5 and 6 having two adjoining interfitting curved edge portions 7 and 8 and having four end members 9 of generally triangular shape. Preferably the plates 5 and 6 are formed of sheet metal and have drainage perforations, such as slots 10 therein. However it will be understood that these plates can be formed of other porous material such as wire screen. The curved edge portions 7 and 8 reinforce and strengthen the plates 5 and 6 and cooperate to form a bottom that a mop will not catch in.

The two end members 9 at each end are arranged so that they overlap each other and the two plates 5 and 6 are pivotally connected with each other by two pivot members 11 which extend

2

through the end members 9 at locations adjacent the curved edges 7 and 8 of the plates. This pivotally connects the two plates 5 and 6 for relative angular movement toward and away from each other on an axis parallel to the adjoining curved edge portions 7 and 8 of said plates.

Preferably at least one perforation or slot 12 is provided in each end member 9 to facilitate drainage of water.

10 10 Preferably spring means is provided to urge the two plates 5 and 6 into a spread apart position. This spring means can be in the form of two spring wires 13 each having a medial loop portion 14 anchored on one of the pivot members 11 and each having two outwardly bent end portions 15 which fit into holes 16 in the end members 9 of the respective plates 5 and 6. One of these springs 13 is provided at each end of the device and said springs normally tend to hold the plates 5 and 6 in a spread apart position such as the position in which they are shown in Figs. 1, 2 and 4. The pivot members 11 preferably are shouldered rivets which are long enough to function as anchor means for the loop portions 14 of the springs 13.

The top edge portion of each plate 5 and 6 is preferably rolled or bent around a reinforcing wire 31 to give added strength and provide a better finish.

The means for suspending this mop squeezing device within a mop pail 17 comprises two pairs of relatively inclined links connected with the respective ends of the mop squeezing device. These two pairs of links and the parts connected therewith are herein shown to be duplicate construction and similar parts thereof are similarly numbered.

Each pair of relatively inclined links comprises two upwardly convergent link members 18 each having an eye member 19 at each end. One 40 eye member 19 of each link is connected with a suitable eye members 20 at the uppermost corner of one of the plates 5 and 6, it being assumed that the adjoining pivotally connected edges of the plates 5 and 6 are their lowermost edges. 45 The other eye member 19 of each link 18 is connected with a mop pail engaging bracket, one such bracket being provided for supporting the two links 18 of each pair. Each mop pail engaging bracket comprises a perforated lobe 21 50 with which two of the links 18 engage, a normally upright portion 22 adapted to engage with the side of a pail 17 and a normally horizontal portion 23 adapted to rest on the top rim 24 of a pail 17. Each rim engaging portion 23 is provided with a fixedly secured upwardly projecting member 25, such as a rivet, on which a loop 26 of

a pail engaging spring clip 27 is supported. Each spring clip 27 has two arms preferably of unequal length which extend in generally opposite directions from the loop 26 and are approximately parallel to the rim engaging portions 23. Each arm of each clip 27 terminates in a hook shaped portion 28 which is adapted to hook over the top rim 24 of the pail 17. The longer arm of each spring clip 27 is sufficiently resilient so that it can be flexed manually and engaged with or disengaged from the rim 24 of a pail. The shorter arm of each spring clip 27 has more stiffness because of its short length and cooperates to firmly hold the bracket 21, 22, 23 on the pail.

In use, this device is suspended in a mop pail in the manner shown in Figs. 1, 2 and 3. A mop, which may comprise water absorbent material 29 carried by a platen 30, Fig. 3, is dipped in water in the pail 17. The water saturated material 29 is then placed in the V-shaped receptacle between the plates 5 and 6 and a downward pressure is exerted against the platen 30. This tends to press the water saturated material 29 downwardly and at the same time the increased load to which the plates 5 and 6 and the two pairs of divergent links 18 are subjected tends to move the plates 5 and 6 toward each other. Thus the absorbent part 29 of the mop is compressed downwardly by the platen 30 and is compressed sideways by the plates 5 and 6 and any desired percentage of the water it carries is evenly squeezed out of the absorbent material.

The foregoing description and accompanying drawings clearly disclose a preferred embodiment of this invention but it will be understood that this disclosure is merely illustrative and that changes can be made within the scope of the following claims.

I claim:

1. A mop wringer for use in a mop pail comprising two rectangular perforated plates having two adjoining lower edge portions and positioned at a divergent angle relative to each other to provide a V-shaped receptacle between said plates; pivot means pivotally connecting the two adjoining lower edge portions of said plates for relative angular movement of the plates; spring means urging said plates apart; and two pairs of links connected respectively with the end portions of the plates and operable to suspend the plates within a mop pail, the two links of each pair having their lower end portions pivotally connected respectively with the two plates near the upper edges of the plates and said two links of each pair converging upwardly and having their upper end portions pivotally supported by the pail whereby downward pressure of a mop in said V-shaped receptacle will angularly move said plates together and compress the mop.

2. A mop wringer for use in a mop pail comprising two rectangular perforated plates positioned at a divergent angle relative to each other with two lower edge portions thereof adjoining to provide a V-shaped mop receptacle between the plates; pivot means connecting the two adjoining edge portions of said plates providing for relative angular movement of the plates toward and away from each other; spring means urging said plates apart; inwardly directed perpendicular rigid overlapping end members on said plates providing end closure means for said V-shaped receptacle; and two pairs of links connected respectively with the end portions of the plates and operable to suspend the plates within a mop pail, the two links of each pair having their lower end

portions pivotally connected respectively with the two plates near the upper edges of the plates and said two links of each pair converging upwardly and being supported by the pail from their upper end portions whereby downward pressure of a mop in the V-shaped receptacle between said plates will press said plates against the mop.

3. A mop wringer for use in a mop pail comprising two rectangular perforated plates positioned at a divergent angle relative to each other with two lower edge portions thereof adjoining to provide a V-shaped mop receptacle between the plates; pivot means connecting the two adjoining edge portions of said plates providing for relative angular movement of the plates toward and away from each other; spring means urging said plates apart; inwardly directed perpendicular rigid overlapping end members on said plates providing end closure means for said V-shaped receptacle; a pair of suspension links provided at each end portion of the two plates, the bottom end portions of the two links of each pair being spaced apart and connected with the respective plates near the upper edges of the plates and the two links of each pair extending upwardly in convergent relation; and readily detachable bracket means connected with the convergent end portions of each pair of links and adapted to be supported from the rim of a mop pail, whereby said plates will be suspended within the mop pail, said links tending to move said plates together in response to downward pressure on said plates.

4. A mop wringer for use in a mop pail comprising two rectangular perforated plates positioned at a divergent angle relative to each other with two lower edge portions thereof adjoining to provide a V-shaped mop receptacle between the plates; interfitting curved portions on the adjoining edges of said plates providing a bottom for said V-shaped receptacle; pivot means connecting the two adjoining edge portions of said plates providing for relative angular movement of the plates toward and away from each other; spring means urging said plates apart; inwardly directed perpendicular rigid overlapping end members on said plates providing end closure means for said V-shaped receptacle; a pair of suspension links provided at each end portion of the two plates, the bottom end portions of the two links of each pair being spaced apart and connected with the respective plates near the upper edges of the plates and the two links of each pair extending upwardly in convergent relation; and means operable to support the convergent end portions of each pair of links from the upper end portion of a mop pail, whereby the plates will hang suspended and divergent in the mop pail and downward pressure of a mop in said V-shaped receptacle will press said plates against the mop.

DAVID JENKINS.
